CLAIM

The ornamental design for a heating module for an electric griddle as shown.

DESCRIPTION

FIG. 1 is a perspective view of a heating module for an electric griddle showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a reduced exploded view of the heating module shown in FIG. 1.
